UNITED STATES PATENT OFFICE.

CLARK E. CARTER, OF MONTREAL, QUEBEC, CANADA, ASSIGNOR TO ALADDIN CINEMA COMPANY, LIMITED, OF MONTREAL, CANADA.

ELECTRICAL CONDUCTOR.

Application filed November 29, 1924. Serial No. 752,915.

This invention relates to improvements in electrical conductors having for an object to provide a novelly constructed resistance conductor especially advantageous for use in supplying electrical energy at a predetermined and required voltage to a receiving means or apparatus from a source whose voltage is prohibitively higher than the loading capacity of said receiving apparatus.

It is likewise an equally important object of the invention to provide a resistance conductor of the character mentioned wherein a novel form of protective covering and insulation is utilized, the relative arrangement of the electrical conductor and of the resistance element being such as to positively insulate the same and to prevent over-heating thereof from that heat radiated by the resistance conductor, during usage, as well as to prevent burning of the casing of the complete conductor or the heating of the same to such an extent as would burn the hands of a person handling it.

Other objects of the invention will be in part obvious, and in part pointed out hereinafter.

In order that the invention and its mode of application may be readily understood by persons skilled in the art, I have in the accompanying illustrative drawings, and in the detailed following description based thereupon, set out one possible embodiment of the same.

In these drawings:—

Figure 1 is a perspective view of a length of my improved resistance conductor; and

Figure 2 is a fragmentary side elevation of the same having portions broken away and shown in section in order that the relative arrangement of the element will be clearly shown.

Having more particular reference to the drawings, in connection with which like characters of reference will designate corresponding parts throughout, the improved device may be stated to comprise an electrical conductor 1, preferably formed of copper wire or other highly conductive material, such as is now common in the art; this electrical conductor being encased in a coating of spirally wound asbestos tape 2 which, as will be noted, completely envelops the same and is in turn, coated and impregnated with a suitable water-proof

dielectric material 3, such material passing into the interstices of the braided or woven asbestos tape casing 2 and serving as an effectual water-proof and insulating covering for the electrical conductor 1. A casing 5 formed of braided asbestos yarn is woven upon the water proof dielectric material 3 encasing and impregnating the asbestos tape 2.

Wound spirally about and over the woven asbestos yarn casing 5 is a resistance wire 4, the same being preferably formed of German silver wire or other material whose properties of electrical conductivity are poor. In this connection, it is to be noted that the coils of the resistance element 4 are spaced with respect to each other which in consequence, will ensure proper functioning of this member.

It is, of course, to be understood that the length of the resistance wire 4 wound spirally over the asbestos yarn casing 5 will be varied according to the desired reduction of voltage to be effected thereby.

About the winding of the resistance 4, a casing of woven or braided asbestos yarn 5' is then laid which if desired, may be impregnated with a water-proof dielectric solution or material, such as hereinbefore indicated by the numeral 3, whereupon a finishing covering or casing of braided or woven cotton or silk 6 is then engaged over this second insulating casing 5'.

To secure practical construction of a cable in accordance with my invention, I have found it extremely advantageous and beneficial to the efficiency of the same to employ asbestos coverings or casings consisting of braided or woven asbestos yarns; it being possible with this yarn to provide a fully enveloping insulating casing at a minimum cost and in a period of time much less than that required in the construction of casings of this particular nature formed of sheet or molded asbestos. The employment of asbestos casings for insulating a resistance is known, but I have found that better results are obtained by loosely weaving the yarn directly upon the resistance. The weaving of these casings 5 and 5' greatly reduces the cost of manufacture thereof as well as producing a more compact and better-appearing conductor. The loosely woven threads permit the spirally wound resistance wire 4 to be imbedded therein, whereby the yarn not

only projects between and insulates the wires of the resistance 4, but retains the latter in their proper spaced relation.

- 5 In usage of the improved cable, it, of course, will be understood that one side of an electrical circuit is connected to one end of the conductor 1 while the opposite side of such circuit is connected to one end of the resistance 4, the length of the complete conductor 1 as well as the length of the resistance wire 4 being such as to effect the desired reduction of voltage from the electrical source of supply, such as conditions or preference may dictate.
- 10 15 Due to the fact that the electrical conductor 1 and resistance element 4 respectively are completely insulated with respect to each other, both through the medium of the casing of spirally wound asbestos tape 5 and the water-proof coating material 3, as well as the braided asbestos 5 it will be understood that dielectric actions will be practically eliminated and that the cable so produced will efficiently function for its intended purpose. Also, by reason of the heat insulating characteristics of the casing 5, the radiation of heat as between the conductors 1 and 4 will not be to such a degree as to injuriously affect either. Furthermore, by 20 covering the cable with the outer casing 5 of braided asbestos yarn, it will be understood that the heating of the complete cable to such an extent as to preclude handling of the same or as to burn the finishing covering 25 or casing 6 will be prevented.

Through braiding asbestos over the water proof coating material 3 as shown and

as above described, uniformity of thickness of heat insulating material is attained without undue attention during the manufacturing process, and further, a proven highly satisfactory means for properly spacing the resistance element coils is formed. This together with the outer layer of braided asbestos coats with the remaining elements 40 45 in the formation of a conductor having the desired resistance to heat radiation, possessing flexibility of a degree facilitating manipulation, and so retaining a spirally wound resistance element that the original 50 spacing of the coils is always assured.

Manifestly, the construction shown is capable of considerable modification, and such modification as is within the scope of my claim, I consider within the spirit of my 55 invention.

I claim:—

A cable comprising, a conductor, a conductor casing comprising a spirally wound asbestos tape, a water proof dielectric material encasing and impregnating the asbestos, a braided asbestos yarn casing for the water proof material, a resistance element spirally wound along and about, and partially embedded in the braided asbestos yarn, the coils of said resistance element being relatively spaced, a second casing of asbestos yarn braided over the resistance element and the first named braided casing, and a finish casing enveloping said second casing. 60 65 70

In witness whereof I have hereunto set my hand.

CLARK E. CARTER.
